UNITED STATES PATENT OFFICE.

GRANT HOLMES, OF DANVILLE, ILLINOIS.

STEAM-SHOVEL.

SPECIFICATION forming part of Letters Patent No. 519,955, dated May 15, 1894.

Application filed January 29, 1894. Serial No. 498,421. (No model.)

To all whom it may concern:

Be it known that I, GRANT HOLMES, of Danville, in the county of Vermilion and State of Illinois, have invented certain new and 5 useful Improvements in Steam-Shovels, of which the following is a specification.

This invention relates to steam shovels, dredgers and the like; it is embodied partly in the dipper construction, partly in the jack 10 brace construction, and partly in the construction and arrangement of the mast head and pulleys therein.

It is the object of the dipper improvement to strengthen the nose piece and provide 15 means for readily attaching and detaching the same.

It is the object of the jack brace improvement to provide strong and effective lateral braces which may be adjusted, and raised for 20 transportation, either by power or by hand. And it is the object of the mast head improvement to lessen the number of pulleys, ordinarily used to guide the hoisting chain, without interfering with the freedom of the 25 swing of the crane.

In the drawings forming part of this specification Figure 1 is a side elevation of a steam shovel embodying the different features of my invention. Fig. 2 is a central vertical 30 section lengthwise through the mast head. Fig. 3 is a front elevation of the mast head. Fig. 4 is a diagram illustrating the swing of the principal pulley of the mast head. Fig. 5 is a central vertical section from front to back through the dipper. Fig. 6 is a perspective representation of the jack braces. Fig. 7 is a detached representation of the 35 jack screw, with its sheave, its clutch and its capstan head. Fig. 8 is a horizontal view of Fig. 2.

The car frame 1 is of any suitable construction, and suitably braced. The brace 2 is secured to the top of the car frame and the top of the jack frame. It extends beyond the 45 front end of the car frame, and it carries on its projecting end the mast head 3. The front end of the mast head is rounded, with relation to the vertical, and it is provided with an arc-formed mouth, or slot 4, through 50 which the hoisting chain 13 travels and swings. A sheave block 5 is pivoted at its lower end on pin 9, which has horizontal bearings in

the lower, front end of the mast head, and extends in line with the length of the head. The sheave 11 is carried by the swinging block 5, 55 and it is in substantial alignment with the vertical pivot of the crane. Vertical pin 10 is secured in the front end of the mast head and it projects upward beyond the same. Block 6 pivots on the upper end of pin 10, being 60 held thereon by collar 7, and it provides a point of connection for the connecting bars 8 of the crane suspending brace 14. Pulley 12 is mounted in the rear end of the mast head between bearings sufficiently far apart to permit 65 sliding motion in the pulley, and the chain 13 runs over pulley 12 and under pulley 11. As the crane swings from side to side, or from center to side, in act of loading and unloading the dipper the pulley 11 swings freely 70 on the horizontal pivot, as indicated in Fig. 4, the chain follows the curved slot, and the pulley 12 moves from side to side, sliding in its bearings, in order to fully accommodate 75 the motion of the chain in the swinging pulley.

The boom of the crane is shown at 15 and the dipper handle at 16. The dipper is constructed in the customary, or any desirable manner, except for the peculiarities herein-after specified, and it is connected with the 80 handle as shown or in the usual manner. The body of the dipper is shown at 17, a band encompassing the upper edge of the dipper is shown at 18, the nose piece at 19, and the teeth at 20. The teeth have the customary 85 external ribs, as 21, 22, which engage the outer surfaces of the nose piece and the dipper body, and are otherwise constructed in the customary manner. A plate, as 23, is bent to fit the inner front portion of the dipper, it is 90 riveted firmly to the upper edge of the body of the dipper, and it is recessed to receive the inner end of the nose piece. A bolt, 24, extends through a hole formed partly in the nose piece and partly in the contiguous vertical wall of plate 23, and, with the assistance of the tooth bolts, holds the nose piece in operative position. The band 18 greatly strengthens the dipper, at the point where greatest strength is needed, and the plate 23, constructed as specified, enables the nose piece to be readily detached for the purpose of sharpening or of replacing with a new nose piece. 95

The jack brace comprises parallel guide

bars 25 which rise from the floor at one side of the front end of the car, extend upward to the top of the car frame, run across the top of the car and extend down to the floor on the opposite side; thereby providing a strong support for the jack braces, and for the mast head. Jack screws 26 have bearings in the car frame between the parallel bars 25, and such screws have loose pulleys 31 at points 10 slightly above the floor of the car, and sliding clutches 32 above the loose pulleys, such clutches being splined on the screws and provided with operating levers as 39, in Fig. 7; and in addition to said pulleys and clutches 15 the lower ends of the screws are provided with capstan heads, as seen at 37 in Fig. 7, whereby the bar 38 may be used by hand to rotate the screw. Nuts 27 are mounted on the jack screws and guided between the parallel 20 bars. A brace bar 28 is hinged in each nut, a tie brace 31 is hinged to a bolster under the car frame, the brace bar and the tie brace are hinged together at their swinging ends, through the intervention of a casting 29, and such casting has a ball at its lower end which 25 fits in a socket in the bearing block 30. The bearing blocks are adjusted, or raised for transportation, by turning the screws in the nuts, and this is done, except in an emergency, 30 by applying power from the engine to the pulleys and throwing the clutches, either or both, in engagement with the pulleys. The power may be applied in various ways, as for instance, the chain 35, which is the chain that 35 operates the dipper, may be geared to run in opposite directions under the manipulation of the operator, and may be diverted through the double pulleys 33 and 34 to the pulleys of the jack screws.

40 The capstan heads on the jack screws bear upward against the bottom of the car and all vertical strain of the braces is thrown onto the heads of the jack screws, to the relief of the parallel guide bars and other parts of the frame.

45 Having thus described my invention, I claim as new and desire to secure by Letters Patent—

1. A crane mast head having a single sheave block approximately in line with the vertical pivot of the crane and swung at its lower end on an approximately horizontal pivot, substantially as set forth.
2. A crane mast head having an arc formed mouth, or slot, for the passage of the chain and provided with a single sheave block approximately in line with the vertical pivot of the crane and swung at its lower end on an approximately horizontal pivot substantially as set forth.
3. A crane mast head rounded vertically on its forward end and having an arc-formed mouth, or slot, for the passage of the chain, and a single sheave block in the mast head approximately in line with the vertical pivot of the crane and swung at its lower end on

an approximately horizontal pivot, substantially as set forth.

4. A crane mast head having a single sheave block approximately in line with the vertical pivot of the crane and swung at its lower end on an approximately horizontal pivot, and also having a sliding sheave to the rear of the swinging sheave block substantially as set forth. 70

5. A crane mast head having a sheave block approximately in line with the vertical pivot of the crane and swung at its lower end on an approximately horizontal pivot, and a vertical pin projecting upward from the mast 80 head and forming a bearing for the suspension rod of the crane boom, substantially as set forth. 75

6. A jack or brace for steam shovels, and similar machines, such brace comprising a jack screw having bearings in the car frame, a nut on the jack screw guided against turning, a brace bar hinged to the nut, and a tie brace hinged to the lower portion of a side of the car, the brace bar and the tie brace being 90 hinged together at their swinging ends and connected with a bearing block, substantially as set forth. 85

7. A jack or brace for steam shovels, and similar machines, consisting in the combination of a jack screw having bearings in the car frame, a nut on the jack screw guided against turning, a brace bar hinged to the nut, a tie brace hinged to the lower portion of a side of the car and also hinged to the 100 brace bar, a bearing block connected with the brace bar and tie brace at or near the conjunction thereof, and a loose sheave and sliding clutch on the jack screw enabling such screw to be turned by a chain of the machine, 105 substantially as set forth. 95

8. A jack screw for adjusting the brace bars of steam shovels, and like machines, such screw having bearings in the car frame and provided with a clutch sheave and a capstan head, whereby it may be operated either by power or by hand, substantially as set forth. 110

9. In jacks or braces for steam shovels, and similar machines, the combination of a guide frame composed of parallel bars extended 115 from the floor at one side of the car upward, across and down to the floor on the opposite side, a jack screw between the vertical bars on each side, a nut on each jack screw guided between the parallel bars, a brace bar hinged 120 to each nut, and a tie brace hinged to the lower edge of each side of the car, the brace bars and the tie braces being hinged together at their swinging ends and connected with a bearing block, substantially as set forth. 125

10. In a dipper for steam shovels, the combination of a dipper; a nose piece; a plate recessed to receive the nose piece, extended around the inner, upper, front portion of the dipper and secured firmly in place; and a bolt 130 extending through a hole formed partly in the nose piece and partly in a coinciding ver-

tical wall of the plate; whereby the nose piece is secured to the dipper in a readily detachable manner, substantially as set forth.

11. In a dipper for steam shovels, the combination of a dipper; a nose piece; a band extending around the upper edge of the dipper; a plate secured firmly to the inner, upper, front portion of the dipper, and recessed to receive the nose piece; and a bolt extending through a hole formed partly in the nose piece and partly in a coinciding wall of the plate, substantially as set forth.

12. A jack or brace for steam shovels, and like machines, consisting in the combination of a jack screw extended through the bottom

of the car frame and provided with a head on its lower end bearing against the bottom of the car, a nut on the jack screw above the floor of the car, such nut being guided against turning, and a brace extending obliquely 20 downward and outward from the nut, whereby all vertical strain of the brace is exerted on the head of the jack screw and against the bottom of the car, substantially as set forth.

In testimony whereof I sign my name in the 25 presence of two subscribing witnesses.

GRANT HOLMES.
